CLAIM

The ornamental design for a multi-use firefighting tool, as shown and described.

DESCRIPTION

FIG. 1 is a front right perspective view of the multi-use firefighting tool;

FIG. 2 is a top plan view thereof;

FIG. 3 is a bottom plan view thereof;

FIG. 4 is a right elevation view thereof;

FIG. 5 is a left elevation view thereof;

FIG. 6 is a rear elevation view thereof; and,

FIG. 7 is a front elevation view thereof.
